Primary Examiner — David Muller(74) *Attorney, Agent, or Firm* — D. Peter Hochberg; Sean F. Mellino; Richard A. Wolf(57) **CLAIM**

The ornamental design for a drain pan, as shown and described.

DESCRIPTION

FIG. 1 is a perspective view of the drain pan according to the invention;

FIG. 2 is a top view of the drain pan as shown in FIG. 1;

FIG. 3 is a bottom view of the drain pan as shown in FIG. 1;

FIG. 4 is a front view of the drain pan as shown in FIG. 1, which is identical to the rear view;

FIG. 5 is a section view of the drain pan as shown in FIG. 2 taken along the line 5-5;

FIG. 6 is a right side view of the drain pan as shown in FIG. 1; and,

FIG. 7 is a left side view of the drain pan as shown in FIG. 1. The broken lines shown in FIGS. 1-6 are for illustrative purposes only and form no part of the claimed design.
